Inventor:

Wm Preiss

United States Patent Office.

WILLIAM PREISS, OF NEW YORK, N. Y.

Letters Patent No. 93,743, dated August 17, 1869.

IMPROVEMENT IN TUCK-CREASING ATTACHMENT FOR SEWING-MACHINES.

The Schedule referred to in these Letters Patent and making part of the same.

To all whom it may concern:

Be it known that I, WILLIAM PREISS, of the city, county, and State of New York, have invented a new and useful Improvement in "Tuck-Markers" for Sewing-Machines; and I do hereby declare the following to be a full, clear, and exact description of the same, reference being had to the accompanying drawing, figures and letters of reference thereon, making part of this specification.

The drawing shows my invention attached to a sewing-machine.

My invention consists in a novel combination and arrangement of parts, whereby I am enabled to make a cheap, simple, effectual, and noiseless tucking-apparatus, which can be readily applied to sewing-machines.

To enable others skilled in the art to make and use my invention, I will describe the construction and operation thereof.

A represents the bed of a sewing-machine, and

B, the vibrating needle-arm, to which I attach, by a clamp-screw, *h*, a forked piece, *a*, to the upper side of which is pivoted, at *g*, the rod *b*.

To the bed or plate, by a screw, *c*, I attach a slotted gauge-plate, *k*, in and upon which the bars *i*, *j*, which are secured together at one end, slide, and the lower piece *j*, at its front end, is provided with a projecting knife-edge, and at the end of the bar *i* is a bearing for a rocking lever, *e*, pivoted at *d*, as plainly shown in the drawing.

To the upper end of the rocking-lever *e* is pivoted, at *e*, a piece through which the rod *b* passes, and the rod is clamped to this piece, in the desired position, by a set-screw, *f*.

Operation.

The operation will be as follows:

By loosing the clamp-screws *c* and *f*, the bars *i*, *j* and the rocking lever can readily be adjusted from the fine of the needle for any desired width of tuck, and firmly held in position by the screw *c*, and this rod *b* is clamped by the screw *f*, so that the notch *e*, in the end of the rocking lever, will force the cloth down upon the projecting knife-edge in the bar *j*, and, as the cloth is fed through the machine, a crease will be made by the conjoint action of the notch *e* in the rocking lever and the projecting knife-edge, as the needle-arm is vibrated.

The power to work this apparatus is derived from the needle-arm, at its centre of motion; the movements of all the parts are slight; there is no making and breaking of contact of parts, as is the case where springs are used, and the apparatus is noiseless and easy in its operation.

Having thus fully described my invention,

What I claim, and desire to secure by Letters Patent, is—

1. The combination and arrangement of the clamp-block *a*, rod *b*, rocking lever *e*, with its jointed arm and screw, provided with a groove, and the projection on the bar *j*, constructed and operating substantially as described and specified.

2. The combination, with the parts above described, of the gauge *k*, for adjusting the apparatus upon the sewing-machine, substantially as described and specified.

WM. PREISS.
